UNITED STATES PATENT OFFICE.

CHARLES A. HINSDILL, OF TROY, NEW YORK.

ADJUSTABLE FIXTURE FOR ELECTRIC LAMPS.

1,305,285.

Specification of Letters Patent. Patented June 3, 1919.

Application filed December 12, 1914. Serial No. 876,840.

To all whom it may concern:

Be it known that I, CHARLES A. HINSDILL, a citizen of the United States, residing at Troy, county of Rensselaer, and State of New York, have invented certain new and useful Improvements in Adjustable Fixtures for Electric Lamps, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in front elevation of an adjustable electric lamp-fixture embodying one form of my invention.

Fig. 2 is a side elevation of the same viewed from the left, as seen in Fig. 1.

Fig. 3 is a side elevation of the same viewed from the right, as seen in Fig. 1.

Fig. 4 is a view similar to Fig. 3, showing only the bracket-member of the fixture.

Fig. 5 is a view in elevation of the inner side of one of the clamping washers.

Fig. 6 is a view in elevation of the inner side of the clamping-disk, which is complementary to the bracket member of the fixture shown in Fig. 4.

Fig. 7 is a vertical section of the upper part of the fixture taken on the broken line 7—7 in Fig. 3 longitudinally of the clamping-bolt.

Fig. 8 is a view in side elevation of a fixture embodying my invention having a different form of attaching base.

Fig. 9 is a cross-section of the same taken on the broken line 9—9 in Fig. 8 viewed in the direction of the arrow.

My invention relates to fixtures for adjustably supporting incandescent electric lamps adjacent to a work-table or bench, and is particularly adapted for use in factories where a considerable number of such lamps are arranged longitudinally of a table permitting them to be mounted upon a common support such as a pipe which forms a conduit for the electric-light-wires.

Certain objects of the invention are to facilitate the mounting of the fixtures upon such a supporting-pipe; and to provide a simple and efficient means for holding in

adjusted position, as to length and angular adjustment, the arms which support the respective incandescent electric lamps.

Other objects will appear in connection with the following description:

Referring to Figs. 1 to 7 inclusive of the drawings, 1 is the bracket-member of the fixture, and 2 is a clamp-disk similar in form to, and complementary to the upper end, 3, of the bracket-member, these complementary members being of circular form and centrally apertured to receive a clamping screw-bolt, 4, whereby they are adapted to be drawn toward each other.

One of these complementary members, as the bracket-member, 1, is provided with a recess, 5; and the other, as the disk, 2, is provided with a tongue or projection, 6, adapted to occupy said recess to prevent relative rotation between the complementary members during the setting up of the bolt, 4, the lug or finger, 6, also serving to support the disk-member, 2, upon the bracket-member, 1.

The clamp thus formed by the complementary members, 2 and 3, is adapted to embrace and hold in adjusted position a length, 7, of metal tubing or pipe of comparatively small diameter, such as will serve as a supporting-arm for an incandescent electric lamp-socket, lamp and shade-holder, and also form a conduit for the electric-supply-wires therefor.

To better adapt the device to thus clamp and hold such a pipe, 7, and also to provide for a wide range of adjustment of the pipe, 7, I interpose between the complementary clamping members, 2 and 3, a pair of clamping washers, 8, centrally apertured to receive the bolt, 4, and provided on their inner sides with complementary grooves, 9, adapted to receive and form a seat for the pipe, 7.

The inner sides of the clamping washers, 8, are further cut away along the outer side of the grooves, 9, to the periphery to provide an open slot, 10, leading to the seat for the pipe, 7, which is formed by the complementary grooves, 9.

This construction permits the pipe to be readily inserted without taking the clamp-members apart, it being necessary merely to loosen the bolt, 4, until the washers, 8, can be sufficiently separated to permit the pipe, 7, to be inserted through the open slot, 10, to its seat, after which the parts can be

tightly clamped together by setting up the screw-bolt, 4.

While the bolt, 4, is loosened, the pipe, 7, can be slid longitudinally within its seat in the washers, 8, as well as rocked or rotated about its axis to secure different positions of adjustment; and the pipe, 7, can be further adjusted in different angular positions relatively to the fixture by rocking or 10 relatively moving the washers, 8, about the axis of the clamping-bolt, 4.

In practice it is often desirable to mount a series of fixtures upon a long pipe extending along a work-bench or table, which pipe 15 forms a conduit for the main electric-supply-wires.

I have shown in Figs. 1, 2, 3 and 4 a preferred form of bracket-base adapted to be readily applied to, and detached from, and 20 adjusted upon, a pipe which base is adapted to be used with various forms of support for the lamp-carrying arm.

This base-portion is substantially U-shaped, forming an approximately semi-circular seat, 11, for the supporting-pipe, 12, the walls of which seat diverge or flare outwardly to form a lateral opening, 13, slightly larger than the diameter of the pipe, 12, permitting the bracket-base to be readily applied to and withdrawn from the pipe, 12, by a sidewise or lateral movement.

The lamp-arm-supporting mechanism is erected from or supported by the upper portion of the U-shaped base, while the lower 35 portion of the base is provided with a screw-threaded aperture adapted to receive a set-screw, 14, which can be screwed inwardly to reduce the width of the outlet, 13, from the seat, 11, to a distance less than the diameter 40 of the pipe, 12, and can be forced into tight engagement with the pipe, 12, to firmly clamp the pipe within and against the seat, 11.

The set-screw, 14, is arranged in a line 45 intersecting the seat, 11, and in a line to exert a direct thrust through the pipe, 12, against a portion of said seat. By thus arranging the set-screw, 14, its thrust is exerted along a line approximately diametrically of the pipe, 12, and this thrust is transmitted in a direct line to, and resisted by, a rigid part of the base portion of the bracket whereby the set-screw serves not merely to prevent the escape of the pipe out through 55 the opening, 13, by restricting the width of that opening, but serves to rigidly clamp and secure the base of the bracket upon the pipe, 12.

Before the set-screw, 14, is set up against 60 the pipe, 12, the bracket, 1, is adjusted rotatably and longitudinally of the pipe to the desired position; and when the set-screw, 14, is tightly set up, the bracket will be securely clamped and locked in the adjusted 65 position.

The set-screw, 14, is slightly unscrewed or loosened to permit the bracket to be removed sidewise from the pipe.

This construction of bracket has great advantage in combination with a conduit-pipe which forms the support for the fixtures, as it permits the fixtures to be mounted upon, and detached from, the pipe at will without taking down the pipe or disturbing the outlets whereby the branch-wires are led 75 out from the conduit.

In Figs. 8 and 9, I have shown an L-shaped bracket, 15, the offset shank, 16, of which is adjustably clamped between a base-clamping-member, 17, fixed upon a stationary support, 18, and a complementary clamping-member, 19, adapted to be drawn toward the member, 17, by means of a screw-bolt, 20.

A finger, 21, on the disk, 19, engages a recess, 22, in the base-member, 17, to prevent relative rotation of the clamp-members.

For certain purposes of the invention, I prefer to make the clamping-washers, 8, wholly or in part of insulating material, 90 whereby in addition to other functions above described, they also serve to completely insulate the lamp-supporting-arm, 7, from the other parts of the fixture.

The main line-wires within the conduit, 95 12, are shown, at 23, in Fig. 2, and the branch-wires for the lamp-arm, 7, are shown at, 24, in Fig. 8.

What I claim as new and desire to secure by Letters Patent is—

100

1. An electric lamp-fixture having in combination a pair of clamping-members, a screw-bolt for drawing said members together, and a pair of clamping washers interposed between said clamping-members, 105 said washers having in their inner sides complementary grooves forming a seat for a lamp-supporting-arm, said screw-bolt passing through said washers.

2. An electric lamp-fixture having in combination a pair of clamping-members, a screw-bolt for drawing said members together, and a pair of clamping washers interposed between said clamping-members, 115 said washers having in their inner sides complementary grooves forming a seat for a lamp-supporting-arm, portions of the inner sides of said washers being removed on the outer side of said seat to form an open slot leading to the seat.

120

3. An electric lamp-fixture having in combination a pair of clamping-members, a screw-bolt for drawing together said members, and a pair of insulated disks embraced between said clamping-members, said disks 125 having in their inner sides complementary grooves forming a seat for a lamp-supporting-arm, said disks being provided with apertures through which said screw-bolt passes.

130

4. An electric lamp-fixture comprising in combination a pair of clamping-members, a screw-bolt for drawing together said clamping-members, and a pair of clamping-washers rotatively embraced between said clamping-members and adapted to be thereby clamped in selected rotative position, said washers having in their inner sides complementary grooves forming a seat for a lamp-supporting-arm.

5. An electric lamp-fixture comprising in combination a bracket having a substantially U-shaped base forming an open pipe-bearing with divergent walls, one branch of said base having screw-mechanism engageable with a pipe inserted in said open bearing, said bracket having an apertured

clamping-member extending from the other branch of said base, another clamping-member complementary to said first-mentioned 20 clamping-member, a screw-bolt for drawing said clamping-members together, and a pair of clamping-disks embraced between said clamping-members and provided in their neighboring faces with complementary 25 grooves forming a seat for a lamp-supporting-arm.

In testimony whereof, I have hereunto set my hand this 10th day of December, 1914.

CHARLES A. HINSDILL.
